Attorney

UNITED STATES PATENT OFFICE

HENRY FRITZ CHRISTOPH MUSMANN, OF DENVER, COLORADO

RAILROAD-CROSSING GATE

Application filed September 23, 1929. Serial No. 394,555.

This invention relates to an automatically operated highway crossing gate for railroads and has for its principal object the provision of a gate of this character which will be simple and efficient in operation; which will be automatically closed as a train approaches and automatically opened by the train as it leaves the crossing.

Another object of the invention is to so construct the device that it will be entirely mechanical in its operation so that it will not depend upon uncertain sources of electricity, compressed air, etc.

Still another object of the invention is to provide a mechanically operated crossing gate in which the shock of operating from a rapidly moving train will be accommodated without damage to the mechanism.

A further object of the invention is to provide means for locking the gates in the open position so that they can not be closed by wind or tampering until actuated by an approaching train.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

25 In the drawing:

Fig. 1 is a perspective view of a railroad crossing with the invention installed thereon.

Fig. 2 is a longitudinal section and side elevation of the gate mechanism.

Fig. 3 is a side elevation of the operating lever mechanism as it appears when the gate is in the open position.

Figs. 4, 5 and 6 illustrate different relative positions of a track dog during its cycle of operation.

Fig. 7 is a side elevation of the track lever mechanism as it appears when the gate is in the closed position.

In Fig. 1 the gates are shown in the closed position. Actually the gates could not be in

this position unless a train were in the "block" between the operating shafts of the gate mechanism. The train has been omitted however, so as not to obstruct the illustration.

In the drawing a highway is illustrated at 10 crossing a pair of railroad tracks 11 and 12. The invention comprises a pair of gate bars 13, pivoted on suitable posts 14 at each side of the tracks so as to drop across the highway 10. The long extremities of the gates 13 are received in socket posts 15 at the opposite side of the highway. The short extremities of the gate are used for attaching the operating cables to be later described.

Operating shafts 16 and 16' are installed under the tracks 11 and 12 a suitable distance each side of the highway. For the purpose of illustration these shafts have been shown in Figs. 1 and 2 relatively close to the highway. Actually they would be more remotely positioned probably about two thousand feet from the highway, depending, of course, upon the speed with which trains cross the particular highway in question.

The operating shafts 16 and 16' are carried in suitable bearings 17 and 17', respectively, and terminate at their extremities in operating levers 18 and 18', respectively. Intermediate the rails of the tracks 11 and 12 track dogs 19 and 20, respectively, are secured to the operating shaft 16. Similar track dogs 19' and 20' are secured to the shaft 16' between the rails of the tracks 12 and 11, respectively.

The extremity of each operating lever 18 is connected by means of a chain or cable 21 to the short extremity of one of the gates 13. The cables 21 pass around relatively large drums 22 positioned in pockets 33 immediately below the pivot posts 14.

Each of the levers 18' is similarly connected by means of a cable 21' with the short extremity of one of the gates 13. The cables 21' pass over idler pulleys 23 and downwardly under the drums 22 before connecting with the gates 13. The cables 21 and 21' pass under guide pulleys 26 immediately ahead of each of the levers 18 and 18'. By this construction, as the levers 18 are swung

100

inwardly they will swing the levers 18' inwardly and will draw downwardly on the short extremities of the gates 13 to lift them to the elevated position of Fig. 2.

5 The extremities of the levers 18 and 18' are constantly pulled outwardly by means of balance springs 24. These springs are designed so as to substantially counteract the weight of the gates 13 allowing a slight excess weight to the gate. Thus, the gates 10 are substantially in a balanced position but if not held open have sufficient excess weight to drop to the closed position and extend the springs 24. In each of the cables 21 and 21' a shock spring 25 is placed so as to absorb the strain of any sudden jerk upon the cables.

It will be noted that when the gates are in the closed position of Fig. 1, the track dogs 20 20 and 19' lie in a depressed position between the rails so as to be inoperative and the track dogs 20 and 20' extend upwardly in an operative position. When the gate is 25 open these conditions are reversed, that is, the track dogs 19 and 19' will be in the operative position, while the dogs 20 and 20' will be depressed.

The locomotives of trains are adapted for 30 operation of the automatic crossing gates by securing a shoe 27 (see Figs. 4, 5, and 6), having a beveled forward extremity 31, along their bottoms. The shoe 27 is supported from a suitable frame structure, such as indicated at 28, upon sliding shafts 29. Shock absorbing springs 30 are positioned 35 about the sliding shafts 29 so as to absorb the shock of the shoe 27 in striking the track dogs.

Let us assume that the gates are in the 40 open position. The operating shaft 16 with its attached levers and dogs will then be in the position indicated in Fig. 3. A train approaches the crossing 10 on the track 11. As it reaches the operating shaft 16 the beveled extremity 31 of the shoe 29 will engage 45 under the extremity of the dog 19. The first shock of engagement is absorbed by the springs 30 and by the action of the beveled extremity 31 in sliding under and gradually lifting the lever 10 so as to give it its initial rotation. Further movement of the train 50 will swing the track dogs through the position of Fig. 5 to the position of Fig. 6. The further movement of the levers is prevented 55 by means of a base block 32 placed thereunder. The lever 19 is maintained in the depressed position of Fig. 6 by the length of the shoe 27 so that it can not rebound.

As the dog 19 swings through the arc 60 above described it will simultaneously swing the levers 18 inwardly, thus slackening the cables 21 and relieving the gates from their support. This will allow the gates to fall by gravity to the closed position. They will 65 reach the closed position approximately at

the time the train shoe 27 leaves the lever 19, and will by their weight maintain the lever 19 in a depressed position.

As the gates 13 fall they will pull upon the cables 21' and rotate the shaft 16' inwardly bringing the track dog 20' to the operative position in track 11. As the train leaves the crossing the train shoe 27 will engage the track dog 20' and swing it outwardly similarly to the process above described with reference to the dog 19. As the dog 20' is forced outwardly by the train it will stretch the shock springs 25 in the cables 21' and will swing the operating levers 18' to a point below the dead center position of the action of these springs, such as illustrated in Fig. 3. Thus, the stretched springs can not swing the levers 18' again inwardly and must exert their tension on the short extremity of the gates 13, so as to raise the gates. The train may have left the shaft 16' far behind before the springs 25 have had sufficient time to overcome the inertia of and raise the gates. By this construction the necessary shock of having the train directly raise the gates is eliminated. The train action only serves to stretch the springs 25. The springs will then re-act to open the gates.

A train approaching the crossing on track 12 will go through a similar series of operations, that is, it will swing the dog 19' inwardly so as to unlock the levers 18' from their dead center position and relieve the tension in the cables 21' so that the gates 100 can fall by gravity to the closed position. After leaving the crossing the train shoe 27 will engage the track dog 20 swinging the levers 18 to the dead center point of Fig. 3 so as to lock them in position, and allowing the tension in the springs 25 to raise the gates.

The invention has been illustrated as applied to a double track railroad. It would operate equally well with a single track in which case both dogs 19 and 20, and 19' and 20' would be positioned between the rails of the one track and the train would be provided with two of the train shoes 27. One of the shoes would be positioned so as to engage the levers 19 and 19' and the other shoe so as to engage the shoes 20 and 20'.

It is desired to call attention to the fact that the operation of the device would not be effected by two trains approaching simultaneously and passing each other within the block defined by the shafts 16 and 16'. The last train to enter the block would not engage any closing lever since the levers 19 and 19' would be depressed at that time. The first train to leave the block would then open the gates.

While a specific form of the improvement has been described and illustrated herein, it is desired to be understood that the same

may be varied, within the scope of the appended claims, without departing from the spirit of the invention.

Having thus described the invention, what is claimed and desired secured by Letters Patent is:—

1. A railway crossing gate comprising: a support adapted to be positioned at the side of a railway track; a gate pivoted to said support; a pair of operating shafts extending under said tracks at each side of said gate; a lever on the extremity of each of said operating shafts; cables extending from the extremities of each of said levers to one extremity of said gate; a drum journaled below said support, both said cables passing about said drum; a tension spring positioned in said cables; a balance spring for each of said levers and operatively connected therewith so as to pull said levers away from said gate; track dogs secured to said shaft between the rails of said track; and means adapted to be carried by a train to engage said dogs so as to rotate said shaft; and a guide pulley for each of said cables, said guide pulleys being positioned so as to maintain said cables in a dead center position with reference to said levers when said gate is in the open position so as to lock said gate in the open position until said track dogs are actuated.

2. A railway crossing gate comprising: a gate support; a gate pivoted in said support so as to have a long extremity extending across said highway and a short actuating extremity; a drum journaled in a pocket below said actuating extremity; an operating shaft positioned at each side of said highway beneath said track; an operating lever secured to the extremity of each of said shafts; cables connecting said operating levers to the short extremity of said gate and passing around said drum; a pair of track dogs secured to each of said shafts, said track dogs being positioned so that when said operating lever is at one extremity of its travel one dog will be in the operative position and the other in the inoperative position and when said lever is at the other extremity of its travel these conditions will be reversed; a spring in said cables; and means adapted to be carried by a train so as to engage a dog or one of said shafts to swing its operating lever and loosen said cable to allow said gate to fall to the closed position and then to engage a dog on the other of said shafts so as to swing its operating lever to stretch the spring in its cable, said levers being arranged to swing beyond the dead center point of the action of said spring so as to prevent said springs from returning said levers.

In testimony whereof, I affix my signature.
